UNITED STATES PATENT OFFICE.

HARLEY R. IRELAND, OF BRAZIL, INDIANA, ASSIGNOR TO HYDRAULIC PRESS BRICK COMPANY, OF ST. LOUIS, MISSOURI, A CORPORATION OF MISSOURI.

BRICK-MACHINE.

1,187,529.

Specification of Letters Patent. Patented June 20, 1916.

Application filed June 23, 1915. Serial No. 35,748.

To all whom it may concern:

Be it known that I, HARLEY R. IRELAND, a citizen of the United States, residing at Brazil, in the county of Clay and State of Indiana, have invented certain new and useful Improvements in Brick-Machines, of which the following is a specification.

This invention relates to brick making machinery, and more particularly to that 10 class of such devices adapted to produce ornamental brick of rough texture.

The primary object of this invention is to construct a machine of the character set forth which shall be adapted to produce 15 fine quality ornamental brick and to stand rough usage and heavy work.

A further object of this invention is to provide a brick making machine adapted to be operated in conjunction with the column-forming apparatus.

A further object of this invention is to incorporate in a machine of the character set forth means for ornamenting the faces of the clay column passed through said machine and also provide means for regulating the depth of the design imparted to the face of the clay column.

A still further object of this invention is to provide a machine of the character set forth which shall be adapted to work with the minimum amount of waste and the maximum amount of efficiency.

With the foregoing and other objects in view as will from time to time appear, this 35 invention consists in the peculiar arrangement and combination of various related parts of a brick making machine as hereininafter described and more particularly set forth in the appended claims.

40 Referring to the drawings forming a portion of this specification and illustrating the preferred embodiment of the invention and wherein similar reference characters indicate similar parts wherever used,

45 Figure 1 is a side elevation of the machine; Fig. 2 is a top plan view partly broken away; Fig. 3 is a detail end view of the side ornamenting means; Fig. 4 is a side elevation of the top ornamenting means.

50 The framework of the machine comprises two similar members 5 bent in approximately U form and provided with inturned feet 6, 6, adapted to be bolted to the top of the measuring table 7 by means of bolts 8, 8.

Each of the members 5 carry collar bolts 55 9, 9 secured thereto by means of screw washers 10, 10 and cap nuts 11, 11. Each pair of collar bolts 9, 9 carries a plate 13, held between nuts 14, 15, which are adjustable along the threaded length of the collar bolts 60 9, thus permitting of the raising and lowering of the plate 13. Each of the plates 13 carries a bearing 16 of any suitable type, adapted to receive a shaft 17, so journaled therein as to permit of lateral movement. 65 The central portion of the shaft 17 is squared at 18 and carries two half cylindrical sections of wood or other suitable material designated at 19, 19, provided with smaller projecting end pieces 20, 20, adapted 70 to be encircled by an iron band 21 held in place by means of tapered pins 22, so as to form a complete cylinder easily removable from the shaft 17. This cylinder carries upon its outer surface a plurality of 75 pins 23 projecting in a radial direction, the purpose of which will be hereinafter described. Upon the shaft 17 is a sprocket wheel 24 and a drive pulley 25.

26 designates a thrust collar of any suitable construction adapted to rotate within a yoke 27 provided with extremities 28, 28, through which pass bolts 29 which engage threaded shoulders 30 upon one of the plates 13. The bolts 29 are provided with wing 85 nuts 31 of relatively larger diameter than the screw threaded portion 29, which prevents lateral movement of the yoke 27. By manipulation of the wing nuts 31, 31 the yoke 27 and consequently the thrust collar 26, and 90 the shaft 17, a transverse adjustment of the shaft 17 within the bearings 16 may be effected, by means of which the proper transverse location of the pin-carrying cylinder may be provided.

95 Bolted to the members 5 at 32 is an upstanding U-shaped member 33 provided with brackets 34 upon each of its legs, which brackets have square openings 35 adapted to receive a transverse rod 36 extending 100 across the machine. Carried by the transverse rod 36 upon both sides of the machine are metal plate 37 provided with leather shoes 38 facing toward the interior of the machine. Intermediate the shoes 38 the rod 105 36 supports a loosely suspended transverse member 39, of leather or other suitable material, the purpose of which will be herein-

after set forth. The upper part of the **U** member 33 is provided with slots 40, 40, adapted to receive bolts 41, which hold bracket members 42 which in turn carry a transverse rod 43 upon which are mounted bars 41 connected intermediate their ends by means of a tie rod 45 and supporting upon their outer extremities, by means of a shaft 46, a large roller 47 covered with sheep skin or other suitable material 48, the purpose of which will be hereinafter set forth. The slots 40 in the bar 33 permit of transverse movement of the two brackets 42, and consequently a transverse movement of the roll 47. A sprocket chain 48 connects the sprocket wheel 24 with a second wheel 49 upon a shaft 50 mounted in bearings 51, 51 and 52, 52, carried by a framework 53 adapted to be bolted or secured in any other suitable manner to the mouth 54 of the clay forming machine. The shaft 50 is of greatest diameter at its central portion 55, where it is threaded at 56, 56, to receive split bushings 57, 57, provided with collars 58 held by set screws 59. From the central portion 55 outwardly upon each side thereof the shaft is turned down to a diameter equal to the base of the threaded portion 56, the inner bearings 52, 52 being of a size to receive this portion of the shaft. Outside of each of the bearings 52, 52 the shaft 50 is again threaded at 60, 60 to receive the lock nuts 61, 61, 62, 62. The bearings 52 are mounted upon the framework 53 by means of bolts 63 which are adapted to slide transversely within slots 64 formed in an extension 53' of the framework 53. This arrangement of the mounting of the shaft 50 permits of transverse movement of the bearings 53 along the shaft 50.

The shaft 50 is provided with two outwardly facing pivotal gears 65 which are slip keyed upon the shaft and adapted to slide along in unison with the bearings 52. The adjustable bearings 52 are provided with vertical journals 66 in their lower portion adapted to receive shafts 67 carrying pivotal gears 68 adapted to mesh with the aforementioned pivotal gears 65. The shafts 67 are provided with cylinders 69 carrying pins 70, the said cylinders being constructed in the same manner as above described for the one carrying pins 23. Thus rotary motion received by the sprocket wheel 49 is transmitted by the shaft 50 to the pivotal gears 65, which engage the pivotal pinions 68, which in turn rotate the vertical pin carrying roll 69. A set screw 71 provided with a lock nut 72 bears against the up-standing portion 73 of a step-bearing 73'. This arrangement is similar upon both sides of the machine and permits of adjustment for the lower end of the roll-carrying shaft 67 in accordance with the adjustment of the upper end, due to the lateral move-

ment of the bearings 52, 52 along the shaft 50. Extending from the upper and lower extremities of each of the pin-carrying shafts 67 are freely swinging pivoted arms 74 provided with a plurality of openings 75 in their outer ends, the said openings being adapted to receive shafts 76 which carry a roll 77 covered with sheep skin or other suitable material 78. Each of the shafts 76 is provided at its lower portion with a thin plate 79 which acts as a bearing for the roll carried by the shaft. The upper pair of pivoted arms 74 is connected by means of a transverse coil spring 80 extending across the machine and the lower pair of arms 74 is connected by a similar coil spring 81, the tendency of these two springs being to draw the arms 74 and correspondingly the rolls carried thereby together.

The operation of the device is as follows: The clay column formed within the machine 54 passes out between the two vertical rolls 69 which are rotated as before described, and which carry pins 70 which cut up and roughen the heads or side surfaces of the clay column passing therethrough. The action of these pins is to partly or wholly detach numerous small particles from the clay ribbon. Passing upon these rolls the clay ribbon comes in contact with the fleece or sheep skin covered rolls carried by the arms 74. These rolls are forced against the side of the heads of the clay ribbon by means of the springs 80, 81, with such force as to roll the clay particles turned up by the pins 70 firmly back upon the clay ribbon in such a manner as to leave an indefinite design or screening the partly filled crevices. From this operation the clay ribbon next passes underneath the two part cylinder 18, 19 carrying the pins 23 which are adapted to cut up numerous particles of clay which are partly or wholly detached from the top of the clay ribbon and lie in a conglomerate mass over its surface. These pins, together with the pins upon the vertical rollers are so spaced that all particles of clay are fairly uniform in size and thoroughly mixed together so as to effectually obliterate any semblance to mechanical or ordered arrangement of design. Passing beneath this transverse roller the clay ribbon is engaged by the transverse leather member 39 which distributes the clay particles turned up by the pins 23 evenly over the shoes of the clay column, being used in this function by the shoes 38, 38, which are directly over the edge of the clay ribbon and which effectually prevent the clay particles from falling entirely off the clay ribbon, or covering what is known as the selvage edge of the said ribbon. The clay ribbon is now engaged by the roller 47 which is covered by fleece 48 which compresses and meets together the conglomerate mass of clay particles before described, thus

uniting them firmly to the clay ribbon proper and placing the finishing touch upon the design.

Any suitable form of conveyer 82 may or may not be placed beneath the clay ribbon in order to support the same during the ornamenting operations.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

Having thus described my invention what I claim as new and desire to secure by Letters Patent is:

1. In a machine for marking a clay column, a marking device mounted to act upon the clay column, means for adjusting the position of said marker vertically to the column, means for adjusting said marker transversely of the column, said vertical adjusting means comprising a bearing, a plurality of supports for the bearing, and means carried by the supports to adjust the vertical location of the bearing thereon, the transverse adjusting means comprising a shaft for the marker, a collar on said shaft and means for shifting the collar to cause the shaft to move transversely to the clay column.

2. In a machine for marking a clay column, a marking device mounted to act upon the clay column and means for adjusting the transverse position of said marker relative to the column, said means comprising a shaft for the marker, bearings for the shaft, a collar on said shaft, and means for shifting the collar to cause the shaft to move transversely to the clay column.

3. In a machine for marking a clay column, a marking device mounted to act upon the clay column, and means for adjusting the transverse position of said marker relative to the column, said means comprising a shaft for the marker, bearings for the shaft, a collar on said shaft and means for shifting the collar to cause the shaft to move transversely to the clay column, said means comprising a yoke on the collar, engaging means on one of said bearings, and an adjustable member between the yoke and the engaging means.

4. In a machine for marking a clay column, a marking device adapted to place a design upon a face of the column by cutting out particles therefrom, and a plurality of members adjacent the marker and extending longitudinally of the column to pre-

vent the particles thus cut from falling off the column and means for simultaneously adjusting the position of the marker and the longitudinal members with reference to the clay column.

70

5. In a machine for marking a clay column, a marking device adapted to place a design upon a face of the column by cutting out particles therefrom, and a plurality of members adjacent the marker and extending longitudinally of the column to prevent the particles thus cut from falling off the column, and means for adjusting the members transversely relative to the clay column.

75

6. In a machine for marking a clay column, a marking device adapted to place a design upon a face of the column by cutting out particles therefrom, and a plurality of members adjacent the marker and extending longitudinally of the column to prevent the particles thus cut from falling off the column, and means for adjusting the members transversely relative to the clay column, said means comprising a support for said members, a shaft, a collar on said shaft, a yoke on the collar, means connecting the yoke and the member support and means for shifting the collar and the shaft.

80

7. In a machine for marking a clay column, a marking device adapted to cut out small particles therefrom, means for preventing the particles thus cut from falling off the clay column, means for distributing the cut particles over the face of the column, and means for simultaneously shifting the members, distributing means and particle holding means, transversely to the clay column.

95

8. In a machine for marking a clay column, a marking device adapted to cut out small particles from the face of the column, and a flexible member extending transversely to the clay column, and adjacent the marker for distributing the cut out particles over the clay column, a plurality of flexible members extending longitudinally of the clay column to prevent particles thus cut from falling off the clay column, and means for simultaneously shifting the transverse member and the longitudinally extending members with reference to the clay column.

100

9. In a machine for marking a clay column, a marking device adapted to cut out small particles from the face of the column, and a flexible member extending transversely to the clay column and adjacent the marker for distributing the cut out particles over the clay column, and means for simultaneously adjusting the transverse position of the distributing member and the marker.

110

10. In a machine for marking a clay column, a marking device adapted to mark the face of the column, a plurality of markers

120

125

130

adapted to mark the sides thereof, a frame, journals on said frame, shafts carrying the side marking devices mounted in said journals, and means for effecting a lateral adjustment of said journals.

11. In a machine for marking a clay column, a marking device adapted to cut out small particles from the face of the column, and a flexible member extending transversely to the clay column and adjacent the marker for distributing the cut out particles over the clay column, a plurality of longitudinally extending flexible members adapted to prevent the cut out particles from falling off the sides of the clay column, means for effecting a movement of the marking device, transverse flexible member and longitudinal flexible members relative to the clay column and means for pressing the cut out particles back upon the clay column.

12. In a machine for marking a clay column, a marking device adapted to cut out small particles from the face of the column, and a flexible member extending transversely to the clay column and adjacent the marker for distributing the cut out particles over the clay column, means for pressing the cut out particles back upon the clay column, means for simultaneously shifting the transverse flexible member and marking device relatively to the face of the clay column; and means for adjusting the pressing means transversely of the clay column.

13. In a machine for marking a clay column, a marking device adapted to mark the face of the column, a plurality of markers adapted to mark the sides thereof, a frame, journals on said frame, shafts carrying the

side marking devices mounted in said journals, means for effecting a lateral adjustment of said journals, said means comprising a central threaded shaft, collars on each end of said shaft, a second threaded shaft engaging each collar whereby turning of said shafts will cause movement of the collars, and means carried by the collar for journaling the marker shafts.

14. In a machine for marking a clay column, a plurality of marking devices adapted to cut the side of the column, a shaft carrying each of said marking devices, a bearing for each of said shafts, means for shifting the bearings transversely relative to the clay column, pressing means adjacent each of said markers, and means for regulating the pressure of said pressing means against the clay column.

15. In a machine for marking a clay column, a plurality of marking devices adapted to cut the side of the column, pressing means adjacent each of said markers, means for regulating the pressure of said pressing means against the clay column, said means comprising pivoted arms carrying said pressing means, resilient connections between said arms to cause the same to be drawn together against the sides of the clay column, and means for simultaneously shifting the marking devices and the pressing means transversely relative to the clay column.

In testimony whereof I affix my signature in presence of two witnesses.

HARLEY R. IRELAND.
